(57) **CLAIM**

The ornamental design for a container cap, as shown and described.

DESCRIPTION

FIG. 1 is a perspective top view of a first embodiment of the invention;

FIG. 2 is a perspective bottom view of the first embodiment of the invention;

FIG. 3 is an end elevational view of the first embodiment of the invention, the opposite end view being identical;

FIG. 4 is a side elevational view of the first embodiment of the invention, the opposite side view being identical;

FIG. 5 is a top view of the first embodiment of the invention;

FIG. 6 is a bottom view of the first embodiment of the invention;

FIG. 7 is a perspective top view of a second embodiment of the invention;

FIG. 8 is a perspective bottom view of the second embodiment of the invention;

FIG. 9 is an end elevational view of the second embodiment of the invention, the opposite end view being identical;

FIG. 10 is a side elevational view of the second embodiment of the invention, the opposite side view being identical;

FIG. 11 is a top view of the second embodiment of the invention; and,

FIG. 12 is a bottom view of the second embodiment of the invention.

In the accompanying drawing the structures shown in broken lines in FIGS. 2, 6, 8, and 12 within the cylindrical bottom collar of the cap and only visible from below are disclaimed; the broken lines are shown for the purpose of illustrating parts of the invention that form no part of the claimed design.

1 Claim, 4 Drawing Sheets
